WIPER-SWITCHING SELECTOR

Reginald Taylor, Liverpool, England, assignor to
 Automatic Telephone & Electric Company Limited, Liverpool, England, a British company

Application November 3, 1949, Serial No. 125,299
 In Great Britain November 11, 1948

12 Claims. (Cl. 179—18)

1

The present invention relates to automatic switches for use in telephone or like systems and is more particularly concerned with final selectors provided with two sets of wipers the required set being connected up in accordance with discriminating means, and with so-called penultimate group selectors which provide access directly over contact banks to said final selectors. The principal object of the invention is to provide improved circuit arrangements for such selectors whereby the number of contacts and the amount of wiring in the penultimate selector bank multiples may be reduced and moreover the number of conductors in the cable connecting said bank multiples to the final selectors may be reduced.

According to one feature of the invention, in a group selector switch the wiper set includes a pair of wipers which are effective alternatively and serve to control wiper selection at a succeeding switch, the mechanical setting of the group selector switch being effected in response only to the odd impulses of a received train which also effect a wiper selecting operation as between the alternative wipers of each set, the reverse wiper switching operation being performed in response to even impulses if any.

According to another feature of the invention, in a group selector switch arranged to be set in response to a train of impulses which cause the intermittent de-energisation of a control relay and provided with a pair of wipers which are used alternatively depending on whether the number of impulses in the train is odd or even, a relay which effects wiper switching is arranged to be energised in response to the first re-energisation of the control relay, to be maintained over a different circuit during the subsequent de-energisation of the control relay and to have its initial circuit opened on the following re-energisation of the control relay.

A further feature of the invention is that in a final selector switch provided with a plurality of sets of wipers the set to be used being determined in accordance with the route over which the switch is taken into use, separate test leads are provided for each access route the remaining leads extending to the switch being common for all access routes.

The invention will be better understood from the following description of typical methods of carrying it into effect, reference being had to the accompanying drawings comprising Figs. 1-5. Although the description has assumed the use of selectors of the two-motion type with so-called

2

rectangular release, the invention is in no way limited thereto.

Fig. 1 shows those circuit elements of a known 200-line final selector which provide for routing of a call to a subscriber in one or other of the two 100-line subscribers' groups in accordance with the speaking path over which the selector is taken into use.

Fig. 2 indicates the modifications to those elements in Fig. 1 to enable call routing to be effected in accordance with the private wire over which the selector is seized.

Figs. 3 and 4, which should be placed side by side with Fig. 3 on the left, show the circuit of a penultimate selector which is intended to provide connection to final selectors having paths of entry of the type shown in Fig. 2.

Fig. 5 shows modifications to the outgoing portion of the selector shown in Figs. 3 and 4 to enable it to be used in conjunction with final selectors employing the known speaking path of entry discrimination arrangements shown in Fig. 1.

The known wiper switching arrangement shown in Fig. 1 is more completely described in United States Patent No. 2,113,119 dated April 5, 1938, and selectors of this type have been employed in conjunction with 200-outlet penultimate selectors of the type described in United States Patent No. 2,504,755, granted April 18, 1950. Such a final selector is normally linked to the penultimate selector bank multiple PSM by five conductors, namely the twisted pair of leads —1 and +1 which are associated with an outlet on an odd level (say level 1) of said multiple, a second twisted pair of leads —2 and +2 which are associated with a corresponding outlet on an even level (say level 2) and a common private lead P1 and P2 which is connected to the private bank contact of each of the said outlets. The use of two twisted pairs is desirable to avoid cross-talk difficulties and the negative leads from the two outlets are connected together at the final selector as indicated. When the final selector is taken into use over the odd level seizing earth is applied by the group selector to lead P1 and P2 and a calling loop is applied to leads —1 and +1 to operate relay AA. Relay AA thereupon operates relay BB (not shown) which at contacts BB1 connects guarding earth to the incoming private lead. The tens digit

45 is subsequently dialled and the wipers are raised to the appropriate level whereupon relay E operates and, in addition to performing the function of directing the units digit impulses to the rotary magnet, at contacts E1 it removes the short-circuit from the left-hand winding of the wiper

switching relay WS. The short-circuit remains removed until the rotary off-normal contacts NR close when the wipers advance into the bank in response to the dialling of the units digit. However, since the conductor +2 has not been employed, relay WS remains normal and determines that the final selector connects over wipers -1, +1 and P1 to that subscriber's line appropriate to the tens and units digits dialled in the odd hundreds group OHG. If that line is idle, relay H operates, applies seizing earth at contacts H3 in known manner and causes the subscriber's bell to be rung. Subsequently when the subscriber answers, the battery feeding relay D is introduced and conversation proceeds. On the other hand if the final selector is taken into use over the appropriate even level of the penultimate selector, seizing earth is again applied to the common private lead but the calling loop is applied to leads -2 and +2. Consequently when contacts E1 open after the tens digit has been dialled, relay WS is enabled to operate on its left-hand winding which is connected in series with the calling loop and the outer windings of relay AA. The lightly adjusted contacts WS1 close and together with other contacts, omitted for simplicity, provide a holding circuit for relay WS. The operated contacts WS2, WS3 and WS4 ensure that, when the units digit has been dialled, the call is routed over wipers -2, +2 and P2 to the appropriate subscriber's line in the even hundreds group EHG.

Reference will now be made to Fig. 2 which where practicable employs the same reference characters as Fig. 1 and may be assumed to be a final selector substantially similar to that described with reference to Fig. 1 except that according to the invention access to it is obtained in a somewhat different manner. In this case a single speaking path of entry is provided over leads - and +, while two separate incoming private wires EP and OP are provided. To appreciate the significance of the path of entry arrangement shown in Fig. 2 it will be necessary to consider its function when final selectors including it are employed in conjunction with penultimate selectors of the type shown in the drawing comprising Figs. 3 and 4.

The penultimate selector shown in Figs. 3 and 4 employs a mechanism of the well-known vertical and rotary type which is preferably, although not necessarily, adapted to enable the wipers to be raised a maximum of five steps instead of ten. The selector is employed in conjunction with four bank contact assemblies each of which however includes only five levels each comprising two rows of eleven contacts each. A total of 440 bank contacts is therefore employed and since the 11th step contacts are not used for normal traffic purposes, it will be permissible to refer to the selector as of the 5/20 type i. e. having five levels each of twenty outlets. The twenty outlets on each level all extend to separate final selectors which embody the private wire path of entry discriminating arrangements shown in Fig. 2, ten outlets extending to first choice final selectors FS1 and ten to second choice final selectors FS2.

When the penultimate selector is taken into use, relay A is operated over its outer windings by the application of the calling loop to the - and + leads by way of the preceding selector GS. Thereupon a circuit is completed by contacts A1 from earth at contacts N4 to operate relay B in series with the vertical magnet VM, the latter remaining inoperative. Relay B on

operating, at contacts B1 provides a holding circuit for itself and prepares impulsing circuits to the vertical magnet and relay OH, at contacts B2 operates relay C in series with resistor YD, at contacts B3 connects earth to the incoming P lead for guarding purposes and to hold the preceding equipment, at contacts B4 prepares a holding circuit for relay HB, at contacts B5 prepares a circuit to the tone winding of relay A, at contacts B6 opens a point in the release circuit which extends to earth by way of delayed alarm equipment over common lead 11, and at contacts B7 prepares to operate relays HA and HB.

When relay C operates at this stage, it prepares circuits for relays HA and HB at contacts C3, at contacts C4 prepares a circuit for short-circuiting its own winding, at contacts C5 opens a point in the locking circuit of relay OH, at contacts C6 short-circuits resistor YB preparatory to the application of impulses to the vertical magnet, and at contacts C7 opens a point in the circuit for the rotary magnet RM. Thus when the selector is seized relays A, B and C are operated.

No further change takes place until the hundreds digit is dialled whereupon relay A responds in known manner to follow the impulses. Upon the first release of relay A, its contacts simultaneously short-circuit relay B and apply full voltage to the vertical magnet VM. Relay B is therefore rendered slow to release while the vertical magnet is operated to actuate contacts VMC and to raise the selector wipers to level 1. The latter action causes the vertical off-normal contacts to operate and these, which remain operated until the wipers are subsequently returned to normal, at contacts N1 prepare the rotary magnet circuit, at contacts N2 prepare the ultimate holding circuit for relay HA or HB and later provide a release guarding circuit, at contacts N3 operate the switching relays HB and HA on their upper and lower windings respectively from earth on the P conductor, and at contacts N4 disconnect the earth which initially operated relay B. Relays HA and HB are now effective in that contacts HA2 and HB1 prepare the outlet testing circuit for relay HA, contacts HB2 prepare a similar circuit for relay HB, contacts HA4, HA6 and HB4 prepare circuits to control relay C, and contacts HA5 and HB6 prepare the rotary magnet driving circuit.

When the loop is again closed after the first break, relay A re-operates thereby permitting the decaying flux in relay B to build up again and at the same time providing a circuit to maintain the vertical magnet operated and to operate relay OH from earth over contacts B1, A1, S1 and VMC, the fairly low resistance middle winding of relay OH, contacts C6 and NR1 and the vertical magnet to battery. Relay OH on operating, at contacts OH1 connects its left-hand winding in series with relay B, at contacts OH2 prepares a holding circuit for itself, at contacts OH3 applies a short-circuit to relay C whereby that relay is rendered slow to release, and at contacts OH4 and OH5 respectively prepares testing circuits to the private wipers OP1 and OP2.

It will be apparent from the foregoing that when digit 1 has been dialled the wipers are raised to level 1 and relay OH is operated. If however a second break is received, relay A releases again whereupon relay B is again short-circuited, the short-circuit is removed from relay C, and full voltage is applied to the left-hand winding of relay OH to hold that relay. At the same time the vertical magnet and the middle

winding of relay OH are disconnected by contacts A1, and the magnet releases to restore contacts VMC. Upon the succeeding make, the short-circuit is removed from relay B whereupon the flux due to the left-hand winding of relay OH is reduced to such a value as to enable that relay to release and relay B is then again connected in series with the vertical magnet which is not now operated. Thus when digit 2 has been dialled, the wipers remain at level 1 but relay OH is normal. Relay C is again short-circuited at this stage.

The penultimate selector continues to function after the manner described if the dialled impulse train includes further impulses, that is to say, the vertical magnet is caused to raise the wipers one step upon each odd break and relay OH is operated on the succeeding make, while the wipers are not raised further by an even break but relay OH is released upon the succeeding make. Thus, by way of example, when digit 7 is dialled, the wipers are raised to level 4 and relay OH remains operated, while when digit 8 is dialled the wipers are raised to the same level but relay OH is released. It may be noted that the alternate energisation and application of a short-circuit to each of relays B and C enables them to remain operated during receipt of the impulse train.

Assume now that the hundreds digit 8 has been dialled, so that the wipers are raised to level 4 and relay OH is deenergised. At the conclusion of the impulse train, relays A and B remain operated but relay C is short-circuited by earth over contacts B1, HA6 and C4 and after a short delay releases. Thereupon at contacts C7 it completes the circuit to the rotary magnet RM in series with the low resistance windings of relays HA and HB. The rotary magnet therefore operates to advance the wipers into engagement with the first set of bank contacts, and towards the end of said advancement to open the interrupter contacts RMC whereupon the magnet is de-energised. During this rotary step, the rotary off-normal contacts also operate and ensure at contacts NR1 that resistor YB remains in series with the vertical magnet, at contacts NR2 and NR3 prepare to disconnect relay A, and at contacts NR4 and NR5 open the initial circuits for relays HA and HB so that these relays are consequently made dependent upon the condition encountered by wipers EP2 and EP1 respectively.

The wipers having advanced on level 4 to the first set of bank contacts which are associated with an outlet to a first choice final selector FS1 and another outlet to a second choice final selector FS2, one of four possibilities now obtains namely, that wiper EP1 connects with the private conductor of an idle outlet while wiper EP2 connects with a busy outlet, that both wipers connect with idle outlets, that wiper EP2 connects with an idle outlet and wiper EP1 with a busy one, or that both wipers connect with busy outlets.

Consider first the possibility in which wiper EP1 encounters an idle outlet as evidenced by the absence of earth, while wiper EP2 encounters a busy outlet denoted by the presence of earth. Under these conditions relay HB releases since its low resistance winding is disconnected at contacts RMC and its upper winding is dependent on the condition of wiper EP1 on which no earth is found. Relay HA is therefore disconnected at contacts HB7 and also releases. The rotary magnet circuit is disconnected at contacts HB6 and HA5 to prevent re-operation of that magnet upon

the closure of contacts RMC. Moreover relay HB at contacts HB2 disconnects its own testing circuit and applies guarding earth to the EP1 wiper to seize the encountered idle outlet, and at contacts HB5 prepares a circuit to re-operate relay HA. Meanwhile relay HA on releasing, at contacts HA4 and HA6 removes the short-circuit from relay C which therefore re-operates, whereupon a new circuit is completed to re-operate relay HA on its lower winding from earth extending over contacts B3, N2 and C3, resistor YC and contacts HB5. Contacts C1 and C2 connect the calling loop through to the wipers and release relay A which short-circuits relay B but, since resistor YB is inserted in series with the vertical magnet by contacts NR1, an earth pulse derived from contacts A1 does not effect said magnet. Contacts C4 together with contacts HA4 provide the ultimate holding circuit for relay C, and contacts C7 disconnect a point in the rotary magnet circuit. Meanwhile the operated contacts HA3 and HA1 connect the calling loop to the -1 and +1 wipers whence they are extended to the - and + conductors of a final selector such as that shown in skeleton form in Fig. 2. It may be mentioned that relay AA in that final selector is consequently operated and in turn operates a relay BB (not shown) which at contacts BB1 connects a guarding and holding earth to lead EP, Fig. 2, and thence to lead EP1 in the penultimate selector. Contacts HA7 in closing maintain a connection between lead EP1 and the incoming P lead upon the subsequent opening of contacts B4. Relay B is short-circuited at contacts A1 and releases after a short delay and at contacts B3 removes the local guarding earth from the P lead, the guarding facility now being provided by earth returned by the seized final selector. Contacts B2 disconnect the initial circuit for relay C, and contacts B6 prepare the driving circuit for the rotary magnet which is to be completed upon the release of the selector. It now follows that the condition of the circuit is such that relay HA remains operated from earth returned to the P conductor over contacts BB1 and E1 and lead EP in the final selector, Fig. 2, and wiper EP1, relay C is maintained operated dependent upon relay HA, and a clear signalling and speech path is extended to the final selector. Later during the inter-digital pause following the dialling of the tens digit when relay E in the final selector operates, the short-circuit is removed from the left-hand winding of relay WS. Thereupon that relay operates, and then holds on its other winding over contacts WS1 in preparation for the closure of the off-normal rotary contacts INR upon the units digit being dialled. Relay WS functions as described in connection with Fig. 1 to route the call to a subscriber in the even hundreds group. It may be mentioned that the resistance of the left-hand winding of relay WS is fairly low so as to maintain a guard condition on lead EP during the period when contacts E1 and NR1 are both open.

In the second before-mentioned possibility when both outlets encountered by the penultimate selector wipers are idle, neither HA nor HB can be maintained over the associated test wiper. Both relays therefore release and thereafter the selector functions in the same manner as in the case just described in that relay C re-operates followed by relay HA whereupon the preferential or first choice outlet associated with wipers -1, +1 and EP1 is taken into use.

Considering now the third possibility, arising

when the penultimate selector wipers encounter the first set of contacts on level 4, in which wiper EP1 encounters earth and wiper EP2 does not. Relay HA releases but relay HB remains operated by the earth extending over wiper EP1 and over contacts B3 shunting the open contacts HA1. Relay HA upon releasing removes the short-circuit from relay C which operates to function somewhat after the manner already described in that in conjunction with operated contacts HE3 and HB1 it extends the calling loop. The idle final selector is seized by the immediate application of guarding earth over private wiper EP2 by contacts HA2 and HB7. During the subsequent connection, relay HB is held operated from earth returned by the seized final selector over wiper EP2, contacts HB7, HA2, N2 and C3, resistor YC, and contacts HE5. Accordingly the incoming - and + conductors are connected to a second choice final selector, again similar to that shown in Fig. 2, over wipers -2 and +2 by contacts HB1 and HB3, while relay C is maintained operated by contacts HB4. As in the other prior examples relay WS in the final selector is operated and the call is routed to a subscriber in the even hundreds group.

In the fourth case, in which both wipers encounter busy outlets, relays HA and HB both remain operated due to the earth conditions encountered by the testing wipers EP1 and EP2. Consequently when the interrupter contacts RMC close again, the rotary magnet is re-energised to advance the wipers to the second set of bank contacts whereupon any one of the four described conditions of the outlets may become operative. It may be mentioned that resistor YA which shunts the rotary magnet is included to control the speed of rotary stepping.

Should the wipers be advanced over the whole group of twenty outlets without encountering an idle one, they will be stepped to the 11th set of bank contacts whereupon the so-called S contacts operate. Contacts S3 consequently open a path in the path to relay HB which releases, and also complete a circuit to operate the overflow meter which terminates on lead 12. Relay HA also releases since, apart from its circuit being broken at contacts HB1, the 11th EP2 bank contact is left unwired. Relay C then operates and is followed by the re-operation of relay HA so that conditions similar to those prevailing in the case of wiper EP1 encountering an idle contact are now established, except that calling loop is reverted by way of the 11th position wiring at banks -1 and +1, to the outer windings of relay A which is consequently steadily energised. It follows that relay B remains operated. At this stage busy tone is made audible in known manner to the calling party by the application of busy tone earth extending from common lead 10 by contacts S4 to the middle winding of relay A which functions as a tone transformer. Contacts S1 prevent the application of a short-circuit to relay C which must remain operated while contacts S2 release relay OH if it has been operated.

Assume now that an odd hundreds digit for instance 7 is dialled. In this case the penultimate selector wipers are raised to level 4, as in the case of digit 8 being dialled but additionally relay OH is operated. It will be apparent therefore that as the wipers eventually advance over the level the same group of outlets will be tested as were tested upon digit 8 being dialled. Meantime on conclusion of the digit 7 impulse train, relay C releases and, in addition to the functions

previously described, provides a holding circuit for relay OH from earth over contacts C4, HA4, C5 and OH2. The wipers advance into the bank as before whereupon the off-normal rotary contacts are now enabled at contacts NR6 to perform the additional function of preparing the ultimate holding circuit for relay OH when relay C finally operates. In this case since OH is operated, contacts OH4 and OH5 present relays HB and HA respectively to the OP1 and OP2 wipers respectively in addition to wipers EP1 and EP2. If a first choice final selector is busy, earth is returned by contacts BB1, Fig. 2, by way of leads EP and OP respectively to the appropriate EP1 and OP1 bank contacts and similarly if a second choice outlet is busy, earth is connected to the appropriate EP2 and OP2 bank contacts. The wipers of the penultimate selector advance into the bank on level 4 and it may be assumed that the outlets are tested after the manner described in connection with the dialling of digit 8. Thus, by way of example, if an idle first choice outlet PS1 is encountered, relays HB and HA release, relay C operates, relay A releases and relay HA re-operates. The latter relay executes its normal functions, including the extension of the calling loop to the seized final selector over wipers -1 and +1, and finally relay B releases. Relay OH remains operated in series with relay C when this latter relay re-operates on the removal of the short-circuit from its winding. Meantime in the final selector relays AA and BB operate and earth at contacts BB1 is connected to lead OP directly and to lead EP over contacts E1. However since contacts OH4 are closed, a full earth is maintained on lead EP over said contacts to short-circuit the left-hand winding of relay WS even during the period elapsing between the operation of contacts E1 and INR preceding the dialling of the units digit. It will be apparent that if this precaution were not taken it would be possible for another penultimate selector, testing the final selector EP lead during said period, to miss-route the call to the even hundreds group by operating relay WS. When an odd digit is dialled therefore, the WS relay of the final selector taken into use remains inoperative and the call is appropriately routed to a subscriber in the odd hundreds group.

It will be evident that had a second choice final selector been taken into use after the dialling of an odd hundreds digit, contacts OH5 would have performed a similar function to that of contacts OH4 explained above.

Referring briefly to the release of the penultimate selector and assuming by way of example that it has been engaged on a call to a subscriber in an odd hundreds group by way of a first choice outlet. When the calling party clears, relays AA and BB in the final selector, Fig. 2, release so that earth is removed by contacts BB1 from the EP1 and OP1 bank contacts to release relay HA. Relays C and OH which are disconnected at contacts HA4 also release and the former immediately places a release guard earth on the incoming P lead over contacts C3 and N2. Relay C at contacts C1 also completes a driving circuit to the rotary magnet from release alarm earth extending over common lead 11 so that the wipers are advanced beyond the 11th step position and continue their so-called rectangular path to the normal position, during which the off-normal contacts NR1 to NR6 restore. When the wipers attain the normal position, the vertical off-normal contacts N1 to N4

restore and the guarding earth is removed from the incoming P lead at contacts N2 so that the selector may be taken into use for another call. It may be mentioned that contacts B7 are included to prevent false operation of relays HA and HB during the releasing operation.

Referring now to Fig. 5 which includes modifications to the outgoing portion of the penultimate selector shown in Figs. 3 and 4 to enable it to be used in conjunction with existing final selectors of the type shown in skeleton form in Fig. 1, it will be appreciated that of the leads associated with one of the first choice outlets, the common negative lead -1 extends to the lead designated -1 and -2 in a final selector Fig. 1, the odd positive lead O+1 connects with the lead +1, the even positive lead E+1 with +2, and the private wire P1 connects with the final selector private wire designated P1 and P2. Each of the second choice outlets FS2 is similarly connected to final selectors.

When a hundreds digit is dialled, the modified penultimate selector functions as already described in that the wipers are raised one step in respect of each odd impulse only and, if the digit is odd, relay OH remains operated at the end of the impulse train, whereas if the digit is even, relay OH is unoperated at the end of the train. Assume that an even digit has been dialled, the wipers advance along the bank level determined by that digit and the outlets are tested as already explained. If a free first choice outlet is encountered, relay HA finally operates and switches the call to that outlet and contacts OH4 ensure that wiper E+1 is employed. Subsequently during the inter-digital pause preceding the dialling of the units digit, the short-circuit is removed from the left-hand winding of relay WS, Fig. 1, which operates in series with the calling loop and the outer windings of relay AA. The operation of relay WS determines that the call shall later be routed to a subscriber in the even hundreds group. When an odd digit is dialled, relay OH remains operated at the end of the train, and, if a first choice outlet is again seized, contacts OH4 ensure that wiper O+1 is used. Consequently relay WS is not operated later and the call is routed to an odd hundreds subscriber. Similar considerations apply when second choice outlets of the penultimate selector are taken into use.

When penultimate selectors embodying the modifications shown in Fig. 5 are employed, it will be necessary in order to reduce cross-talk interference, to suitably twist together the three speaking conductors throughout the bank multiple and the inter-connecting cable.

I claim:

1. In a group selector for use in a telephone system, a first relay arranged to be operated intermittently in response to a train of impulses for setting the switch, a stepping magnet, a set of wipers including a first wiper and a second wiper, a second relay arranged to render effective one or both of said first and second wipers determined by its state of de-energization or energization, a first winding on said second relay, means for energizing said second relay by way of said first winding in series with said stepping magnet in response to the first re-energization of said first relay, a second winding on said second relay, means for maintaining said second relay operated over said second winding during the subsequent de-energization of said first relay and means for preventing the completion of the initial circuit through the first wind-

ing of said second relay when said first relay again energizes.

5 2. In a telephone system, a final selector switch, a plurality of sets of wipers for said switch, means for operating said final selector from any one of a plurality of means of access, incoming speaking leads common to all the means of access, a plurality of separate incoming test leads individual to the different means of access, and switching means for causing a particular set of wipers to be effective dependent on the particular test lead used.

10 3. Switching apparatus claimed in claim 1 comprising, in addition, a relay controlling wiper selection means for the succeeding switch, a test circuit in which said alternately effective wipers are included for cooperation with the said relay controlling wiper selection and adapted for connection between the test contacts.

15 4. The switching apparatus claimed in claim 3 comprising, in addition, means including a second switch for connecting the test wipers together in one of the operating conditions to avoid operation of the relay in the selected succeeding switch at the same instant through the wiper providing a series circuit for said relay.

20 5. The switching apparatus claimed in claim 1 comprising, in addition, a driving magnet, a series circuit including the relay, contacts controlled by the magnet and the make contacts of the control relay for initially energizing the relay.

25 6. The switching apparatus claimed in claim 1 comprising, in addition, contact elements for the relay connected to change the impulsing connection from the break contacts of the control relay from the magnet to its own winding.

30 7. The switching apparatus claimed in claim 6 comprising, in addition, a third relay having a break contact element, and means to maintain the control relay operation including a circuit of which the break contact forms a part, said relay remaining energized when the number of impulses in the train is odd and releasing when the impulses series ceases.

35 8. In a telephone system, a group selector comprising a set of wipers including a first wiper and a second wiper, a set of bank contacts for each of said wipers, a plurality of succeeding switches each having a plurality of sets of wipers, connections extending from said sets of bank contacts to said switches, means in said group selector for completing a control circuit over either said first wiper or said second wiper to effect wiper selection in a selected one of said succeeding switches, means in said group selector for responding to a train of impulses, means responsive to the odd impulses of said train for effecting mechanical movement of said set of wipers including said first wiper and said second wiper and for transferring control from said first wiper to said second wiper and means responsive to any even impulses of said train for transferring control from said second wiper to said first wiper.

40 9. The group selector claimed in claim 8 comprising, in addition, means to establish group selecting movement of the wipers in a vertical direction and means to establish hunting movement of the wipers in a rotary direction.

45 10. The group selector claimed in claim 9 in which the bank for each wiper comprises a unit of five levels only.

50 11. In a telephone system, a final selector switch having a plurality of sets of wipers, a plurality of control paths, means for operating said final selector from any one of the plurality of

11

paths, incoming speaking leads common to all of said paths, a plurality of separate incoming test leads individual to the different paths, switching means for causing a selected one of the plurality of sets of wipers to become effective in accordance with the particular test lead currently used, a relay for controlling the set of wipers to be used, and means for connecting the relay winding of the set of wipers to be used in series with the test lead corresponding to one of the 10 separate control paths during the interval between two trains of impulses to which the switch responds.

12. A telephone system comprising a final selector switch, a plurality of sets of wipers for said switch, a plurality of control paths, incoming voice connections common to all of the control paths, a plurality of separate incoming test leads

12

individual to the several paths, switching means controlled from the test leads for causing one set of wipers to become effective on a selected test lead, and means for causing the first digit received to effect movement of the wipers in a vertical direction, and a second digit received to effect movement of the wipers in a rotary direction.
